UNITED STATES PATENT OFFICE

2,574,848

FEATHER DRYING SYSTEM

Arthur M. Schroeder, Chicago, Ill.

Application May 18, 1946, Serial No. 670,661

5 Claims. (Cl. 34—2)

1

This invention relates to driers and more specifically to feather driers arranged for continuous performance at high efficiency operation under substantially automatic performance in a system that can be readily controlled for uniform output of dried feathers.

One of the main objects of this invention is to provide an arrangement of connected units each contributing successively to the cycle of handling feathers from a wet state to a perfectly dry state, and which arrangement of units simultaneously permits continuous operation as long as wet feathers are introduced for drying.

Feather drying equipment in the past has generally utilized driers having forced air blowers at the entry end thereof to eject the wet feather and air mix into the inlet end of the driers. This has not been satisfactory because wet feathers or bunched groups thereof would be ejected at times from the drier through the direct action of the blower fan blades. Also, at times during the passage of feathers to the blower and into the drying chamber, wet feathers would be brought in balls or groups by the air stream from the feed inlet, and upon contacting the fan blades of the blower, such groups or balls would be forced against the sides of the drier by tangential or radial ejection from the blower fan blades. This is noisy and also causes deformations of the drier walls from the impact.

In addition, when the blower is housed within or forms a part of the inlet end of the drier, feathers will stick or pack to the fan blades of the blower under certain conditions of operation. This creates an unbalanced relation inducing an off center load which sets up vibration in the blower and the entire drier unit as the fan rotates producing undesirable results that are obvious.

The system and units of the present design have been so constructed and arranged as to overcome the above objections and limitations thereby providing advantages that are self-evident. The system is mainly operated under suction with certain pressure zones for definite purposes. The drying chamber is acted upon by suction from above to draw the air and feather mix out of such chamber. The bag filler is also subjected to suction as an efficient attribute to completely filling a bag in a relatively short interval.

One pressure zone is established ahead of the heater and feeder, but such air stream will lose some of its kinetic energy at the time it reaches the drier although it will still blow wet feathers into the drier to pile up in the bottom thereof, while advancing dried feathers up the chamber to be drawn out by the vacuum at the top thereof as created by the suction side of a blower. Another pressure zone is created beyond the last

2

named blower to convey the dried feathers to a bag filler or other storage place as the case may be. Pressure in the latter zone is dispersed by novel means substantially automatic in operation as the bags are being filled.

It is another object of this invention, therefore, to provide such automatic pressure relief means to allow loss of free air from the inlet side of the filler and from within a bag being filled to accommodate air dispersion which is normally reduced as a bag fills with more and more feathers until full.

Another object of the present invention is to provide a multiple bag filling chamber wherein the feathers are forced under pressure into the receiving bags and at the same time a lower pressure or partial vacuum as explained above is maintained about the bag being filled to greatly minimize the filling time and to introduce a greater concentration and weight of feathers into the bags in comparison with past practice and experience. By reason of the multiple bag filling chamber, the bags may be changed providing continuous filling and replacement of bags.

There are other objects and advantages present in the feather drier design representing a preferred construction thereof which will herein-after appear in the following detailed description thereof having reference to the accompanying drawings forming a part of this specification.

In the drawings:

Fig. 1 is a front elevational view of a preferred arrangement of connected units diagrammatically illustrated and adapted to carry out the function of drying feathers; and

Fig. 2 is a plan view of the general arrangement shown in Fig. 1 and diagrammatically illustrating further details of construction of the same system which contribute to the success of the drier.

The preferred design of feather drier as portrayed in the drawings begins with a heater 1 adapted for heating air supplied thereto through a suitable inlet duct 2, such air being heated to a selected temperature best suited for the amount of feathers being dried. From experience it has been found that 300° F. is a good temperature at which to discharge air through the outlet duct 3 of the heater 1 and into the feeder 4 through which the wet feathers are introduced into the system for drying.

The heater 1 may be heated in any manner feasible for supplying heat to the circulating air of the system. In Fig. 2, a steam coil 5 is used to provide the necessary heat. Gas, oil, electricity or any other energy-producing means may be used to supply heat to the system, and conventional thermal responsive means may be used to hold the exhaust air in duct 3 at 300° F. or at a predetermined temperature that may be desired.

and controlled through manual setting of the conventional thermal responsive means.

From the heater 1, the air enters duct 6 which is arranged for vertical discharge along an offset path by means of a bottom inlet duct 7 leading into one side of the bottom of a vertically disposed feather drying chamber 8 that is narrow but relatively long to give the feathers a turbulent and tumbling action. The feathers enter chamber 8 with the heated air coming from the heater 1 when the feathers are fed into the system through the feeder 4. In chamber 8 the wet and partially wet feathers tend to drop or descend at various rates toward the bottom end portion 6a of the chamber 8 as in Fig. 2 and toward the inlet duct 7, while the drier feathers tend to rise upwardly toward the outlet duct 9 leading from the expansion chamber 10 forming the upper end of the chamber 8. Thus, wet and dry feathers or partially wet and partially dry feathers pass each other or collide at different altitudes within the drying chamber 8, but in all cases the strictly dry feathers will rise and pass through the expansion chamber 10 and out through the outlet duct 9 into the suction side 25 of the hot air blower 11. The general turbulence and intermingling of the feathers can be viewed through either of the glass windows 12 and 13 on the side of the drying chamber 8 by shining a light through the other glass window. The violence of the action observed will permit adjustments to be made for reducing or increasing such action by changing motor speeds or the drives to the blowers or by regulating the dampers of the system and more particularly the damper 57 in duct 54.

The action of the expansion chamber 10 is to provide a chamber having a larger transverse cross-sectional area than the transverse cross-sectional area of the main chamber 8 to momentarily decrease the flow of air carrying mostly dry feathers to the outlet duct 9 thereby giving feathers that may still be wet or slightly damp which reach this part of the drying chamber an opportunity to descend again a sufficient amount to become completely dried and to be subsequently carried upwardly and out of duct 9 to blower 11.

From blower 11 the air and dried feather mix is discharged into duct 14 to be conveyed to the bag filler 15. The air is now at about a temperature of 200° F. which is approximately the temperature at which the feathers are forced, under pressure of the blower 11, into the feather receiving bags disposed in the filler 15.

To provide a filler capable of continuous reception of feathers and having bags disposed to always accommodate the feathers coming through duct 14, the filler 15 has at least two compartments 16 and 17, each having appropriate releasable bag holding means 18 and 19, respectively, to receive bags such as 20 shown in operative feather receiving position with the holding means 18 and in compartment 16. Each compartment 16 and 17 has corresponding doors 21 and 22 for loading purposes hinged to the filler 15, with suitable handles 23 and 24 placed in positions for the convenience of the operator of the filler 15.

The compartments 16 and 17, and their respective bag holding means 18 and 19 are served by a manifold 25 into which the duct 14 discharges the air feather mix. A damper 26 is located centrally of the manifold 25 and functions to divert the air feather mix to either of the filler compartments depending upon its position. As shown in broken lines in Fig. 1, the damper 26 is

diverting the air feather mix into the compartment 16 and into bag 20 there shown. By moving damper 26 into the dot and dash line position in Fig. 1, the air feather mix would be diverted to a bag supported in compartment 17.

Damper 26 may be suitably operated by a chain, wire or cord 27 passing over and secured to a pulley 28 carried by the damper shaft 29 as best seen in Fig. 1. Convenient hand grip balls 30 and 31 painted a striking color or colors may be secured to the loose ends of the cord 27, and the latter may be of such a length as to cause one of the balls to always occupy a position adjacent one of the door handles as a visual means to indicate to the operator which compartment of the filler 15 is in operation. As seen in Fig. 1, ball 30 is down next to the door handle 23 to indicate that compartment 16 has a bag in receiving position and damper 26 is automatically tilted to serve the bag 20 in compartment 16.

As bag 20 is being filled in compartment 16 with feathers under pressure from blower 11, a second blower 32 is employed for exhausting the air from the compartment 16 and from about the bag 20. Exhaust blower 32 is connected with the compartments 16 and 17 of filler 15 by means of a common duct 33, through a manifold 34, and through the dual ducts 35 and 36 as best illustrated in Fig. 2. Suitable screens 37 and 38 are vertically positioned within and rearwardly of the chambers 16 and 17 respectively to prevent feathers, foreign materials or other matter from entering the drying system through means of the suction created by the blower 32 in either of the ducts 35 or 36.

Manifold 25 provides a feather receiving chamber which generally covers the top of the filler 15 and has a solid central top section 14a to receive duct 14, and suitable screens 16a and 17a, as best shown in Fig. 2, flank section 14a and cover the upper ends of the manifold portions above the compartments 16 and 17. The screens 16a and 17a are selected according to conditions of operation and may be carried in interchangeable frames. The screen sizes may also be varied to suit operating conditions effected by the location of the drying systems and/or the humidity variations at the site of installation.

Suction through either of the ducts 35 or 36 is controlled by a damper 39 in manifold 34. When damper 39 is in the broken line position in Fig. 2, suction prevails in compartment 16, but if moved into the dot and dash line position, compartment 17 will be under suction. The action of damper 39 is synchronized with the action of damper 26. This is done by extending the shaft 29 of damper 26 to drive a vertical shaft 40 through gears 41 and 42 and by means of the drive being transmitted from shaft 40 through a belt 43 connected with a pulley 44 secured to the shaft 45 of damper 39.

Each compartment 16 and 17 has air intake ducts 46 and 47 with dampers 48 and 49 controlling the inlet openings of each of the ducts respectively. Deflecting baffles 50 and 51 direct the cooler inlet air downwardly into the compartments of the filler 15. The inlet air that enters either of the compartments will mix with the air forced and sucked through the feather bags 20 reducing the temperature in the compartments to approximately 140° F. In this manner, the air in the compartments is cooled, dropping the pressure in such compartments to aid the exhaust blower in producing the pressure differential between the interior and exterior of the

bags 20, the air coming in through ducts 46 and 47 also replenishing air loss from the system.

The pressure differential is also established through a differential speed operation or by the selection of the capacity ratings of the two blowers 11 and 32. Blower 11, driven by a motor 52, delivers approximately 3000 cubic feet of air per minute in this installation; while the blower 32, driven by a motor 63, exhausts approximately 4000 cubic feet of air per minute. These figures as well as others that may be stated are exemplary and do not represent any limitations in the operation of the feather drier of the design herein disclosed. Also, while the device has been shown having two bag filling compartments, it is contemplated to use three or more such compartments with multiple damper controls to regulate the feather delivery and the evacuation of air from each selected bag filling compartment.

Screens 16a and 17a function as a means for diverting free air from within the bags within the compartments 16 and 17 during the time the bags are being filled. A bag such as 20 in compartment 16 will allow most of the air carrying feathers through duct 14 to pass through the bag fabric and to be withdrawn by the exhaust blower 32. Very little will initially pass through the manifold screen 16a since the feather air mix will follow the course of least resistance. As the bag begins to fill, the feathers will gradually fill the bag closing the fabric to air passage so that the air from duct 14 will automatically be released through screen 16a in steadily increasing amounts. Part of the air will still go into the bag delivering feathers thereto and such air is drawn off through the suction of blower 32, depositing a concentration of feathers within the bag until such bag is completely filled.

Obviously some feathers will cling to the screen 16a because of the bypassed air bleeding therethrough, but the area and mesh of the screen is made large enough to permit the passage of free air to efficiently carry out the bag filling operation. Such feathers will drop off of the screen when the air is diverted to the other compartment. Any feathers left on the screen will subsequently be drawn into an empty bag when the immediate compartment is again set in operation.

To complete the cycle of operation of the system, exhaust blower 32 withdraws air from the filler 15 or from the respective compartments thereof and forces such air through a duct 54 back to the intake duct 2 of the heater 1. This air will carry some moisture due to the lower temperature of about 140° F. from the initial 300° F. in the drying chamber 8 due to natural condensation so that a suitable vent means is interposed in the last part of the cycle of operation of the drying system to allow for diversion of some of the moisture and air prior to reentering the heater 1.

This is accomplished by means of the vent duct 55 that connects with duct 54 between blower 32 and heater 1 and this vent duct may be arranged to discharge bypassed air and moisture through a wall or ceiling of the building to atmosphere. A damper 56 is shown in Fig. 1 having suitable regulatory mechanism 57 for controlling the angular position of the damper to regulate the amount of air and moisture diversion necessary to obtain the best results for continuing the feather drying process described.

Duct 55 will also serve to permit air to reverse therethrough and enter the drying system if the

suction of air is interrupted from the filler to the blower or through a blower breakdown as the case may be. It is possible that one of the screens 37 or 38 may become clogged with feathers as may occur from a break in the fabric of a bag being filled. The suction of blower 32 would then draw the feathers out of the bag and up against the vertical screen. Screens 37 and 38 are also made large enough to forestall any blockage that would cause serious interference with the operation of the drying system. At any rate, the system may be kept in operation long enough to clear the feathers out of the ducts and drier if necessary, or to switch the filling operation to another filler compartment until the condition causing air flow retardation is found and remedied.

Changes and modifications in the exact design, construction and combination of units or parts as well as substitution of equivalent mechanisms are contemplated in the feather drying system. Such deviations in the design of this invention shall be governed by the scope of the appended claims directed thereto.

What I claim is:

1. A feather drying system comprising a drying chamber, a heater, a first blower to force air through said heater into said drying chamber, a feed means to feed wet feathers into the hot air stream in advance of said drying chamber, a second blower to draw dry feathers and hot air out of said chamber, a bag filling compartment connected to receive said air feather mix, means in said compartment for releasably supporting a bag in a position to catch the feathers from said second blower, and a conduit connected between said filling compartment and said first blower to exhaust air from the space within said compartment and surrounding said bag, said first blower having a greater volumetric capacity than said second blower to produce a lower pressure in the filling compartment space surrounding the feather receiving bag than in the interior of said bag.

2. A feather drying system comprising a drying chamber, a heater, a first blower to force air through said heater into said drying chamber, a feed means to feed wet feathers into the hot air stream in advance of said drying chamber, a second blower to draw dry feathers and hot air out of said chamber, a bag filling compartment connected to receive said air feather mix, means in said compartment for releasably supporting a bag in a position to catch the feathers from said second blower, and a conduit connected between said filling compartment and said first blower to exhaust air from the space within said compartment and surrounding said bag, said first blower having a greater volumetric capacity than said second blower to produce a lower pressure in the filling compartment space surrounding the feather receiving bag than in the interior of said bag.

3. A feather drying system comprising a drying chamber, a heater, a first blower to force air through said heater into said drying chamber, a feed means to feed wet feathers into the hot air stream in advance of said drying chamber, a second blower to draw dry feathers and hot air out of said chamber, a bag filling compartment connected to receive said air feather mix, means in said compartment for releasably supporting a bag in a position to catch the feathers from said second blower, and a conduit connected between said filling compartment and said first blower to exhaust air from the space within said compartment and surrounding said bag, said first blower having a greater volumetric capacity than said second blower to produce a lower pressure in the filling compartment space surrounding the feather receiving bag than in the interior of said bag, and an atmospheric bleed duct for said filling compartment to allow cool air to enter the space around said bag reducing the temperature of the air in said space and to supply fresh air to said drying system, said bleed duct having adjustable control means to regulate the amount of air entering said filling compartment.

4. A bag filling device for a feather drying system comprising at least two bag filling compartments, a first blower to supply dried feathers and air under pressure to said compartments, a second blower to exhaust air from said compartments and from the space surrounding the bags in said

compartments, cooperative dual duct means leading from said first blower to the compartments and from the latter to said second blower, and synchronized damper mechanisms for said dual duct means connected to alternately serve one or the other of said compartments whereby a full bag of feathers may be withdrawn from either compartment and replaced with an empty one.

4. A bag filling device for a feather drying system comprising at least two bag filling compartments, a first blower to supply dried feathers and air under pressure to said compartments, a second blower to exhaust air from said compartments and from the space surrounding the bags in said compartments, cooperative dual duct means leading from said first blower to the compartments and from the latter to said second blower, and synchronized damper mechanisms for said dual duct means connected to alternately serve one or the other of said compartments whereby a full bag of feathers may be withdrawn from either compartment and replaced with an empty one, said second blower having a greater volumetric capacity than said first blower to produce a lower pressure in either of said compartments in the space surrounding the bag than within said bag during the operation of a compartment.

5. A bag filling device for a feather drying system comprising at least two bag filling compartments, a first blower to supply dried feathers and air under pressure to said compartments, a second blower to exhaust air from said compartments and from the space surrounding the bags

in said compartments, cooperative dual duct means leading from said first blower to the compartments and from the latter to said second blower, and synchronized damper mechanisms for said dual duct means connected to alternately serve one or the other of said compartments whereby a full bag of feathers may be withdrawn from either compartment and replaced with an empty one, said compartments having individual doors for ingress thereto, and said synchronized damper mechanism having operating means connected therewith to provide visual means each disposed at a predetermined position with respect to said individual doors to indicate which compartment is in operation.
